[57] CLAIM

The ornamental design for a lotto number choosing board game, as shown and described.

DESCRIPTION

FIG. 1 is a top plan view of the lotto number choosing board game showing my new design;

FIG. 2 is an end elevational view thereof, the end opposite and both sides being mirror images of the end shown in FIG. 2 with the exception that the sides are longer than the end shown; and,

FIG. 3 is a rear plan view thereof.

FIG.1

FIG.2

FIG. 3
